(57) **CLAIM**

The ornamental design for a beach cart, as shown and described.

DESCRIPTION

FIG. 1 is a perspective view of a beach cart design showing my new design.

FIG. 2 is a front view of the beach cart.

FIG. 3 is a rear view of the beach cart.

FIG. 4 is a left side view of the beach cart.

FIG. 5 is a right side view of the beach cart.

FIG. 6 is a top view of the beach cart.

FIG. 7 is a bottom view of the beach cart.

FIG. 8 is an enlarged portion taken from line 8 in FIG. 2.

FIG. 9 is an enlarged portion taken from line 9 in FIG. 6; and,

FIG. 10 is an enlarged view taken from line 10 in FIG. 5. The broken lines in the drawings indicate enlarged portions which form no part of the claimed design.
